TOY FIREARM

Rice Tomita and Kenichi Tomita, Puunene,
Territory of Hawaii

Application December 18, 1935, Serial No. 55,108

2 Claims. (Cl. 124—14)

This invention relates to toy firearms of that character which uses a rubber band as a projectile.

One of the principal features of the invention 5 is a novel construction that permits a single trigger bar to be utilized for a band gripping portion and a finger gripping portion.

Another feature of the present invention is the design of the band gripping portion of the 10 trigger bar which has a compound curvature to hold two or more projectile bands in position to be selectively released at different positions of the trigger bar.

Further objects of the invention are to provide 15 a toy of the character referred to that is strong, compact, durable, very entertaining to the children, that is thoroughly efficient for its intended purpose and comparatively inexpensive to manufacture.

With the foregoing and other objects in view 20 the invention consists of a novel construction, combination and arrangement of parts as will be hereinafter more specifically described and illustrated in the accompanying drawings and 25 specification, but it is to be understood that changes, variations, and modifications may be resorted to without departing from the spirit of the claims hereunto appended.

In the drawings wherein like reference characters 30 denote corresponding parts throughout the several views:

Figure 1 is a side elevation of the toy firearm 35 constructed in accordance with the present invention and showing a pair of rubber bands in position to be projected thereby.

Figure 2 is a top plan view thereof.

Figure 3 is a front elevation thereof.

Figure 4 is an enlarged fragmentary portion 40 thereof taken substantially on the plane of line 4—4 of Figure 1.

Figure 5 is a fragmentary detailed vertical section taken through the plane of the trigger bar slot and showing the trigger bar in cocked relation.

Figure 6 is a view similar to Figure 5 showing 45 the trigger bar in position for releasing both bands.

Figure 7 is a side elevation of the trigger bar removed from the body of the firearm.

Referring to the drawings in detail it will be 50 understood that the body of the toy firearm is to be made to simulate a pistol or rifle. The body of the firearm is preferably made in one piece out of wood or other material and consists 55 of a barrel portion 10 which at its rear end

merges with a depending stock or handle portion 11. In the body of the firearm illustrated I have simulated the design of a conventional automatic pistol, but it will be understood that the principle of the invention may be applied to other pistols 5 and rifles.

Forwardly of the point where the barrel 10 merges with the handle 11 there is formed a slot B which extends vertically through the barrel. From a point in the middle of the slot the forward wall thereof inclines forwardly and outwardly as shown respectively at 12 and 13. The rear wall of the slot B beginning at a point in the middle of the slot also inclines outwardly and rearwardly as indicated respectively at 14, 15. 15 The angular inclination of the forward and rear walls of the slot cooperates with the trigger bar to retain it in cocked relation in one position and band releasing position in the other position. The former and latter positions are clearly illustrated in Figures 5 and 6 of the drawings. 20

There is a pin 15a mounted in the rear portion of the barrel 10 having the intermediate portion spanning the slot B. The middle of a flat trigger bar C rocks on the pin 15a within the 25 slot B. The trigger bar C has a finger gripping portion 16 extending below the lower extremity of the slot whereupon the finger of the operator rocks the trigger on the pin 15a. The trigger bar C also has a portion 17 projecting above the barrel 10 and free of the slot B and this portion 17 is utilized to grip the rear ends of two elastic bands 18, 19. The rear edge of band gripping portion 17 has two segmental notches 20, 21 merging with each other at a rib 22. A tangent 30 to the segments is located in a position at an angle to the barrel 10.

The rear portion of the barrel 10 has an extension 23 depending therefrom and in this extension is a bore 24. The forward end of the 40 bore opens at the forward end of the extension 23, and the rear end thereof registers with the lower portion of the slot B. In the forward end of the bore 24 there is a pin 25 fixed in the walls of the bore. An eye 26 on the forward end of 45 a helical coil spring 27 secures one end of the spring to the pin 25. The body of the spring is mounted in the intermediate portion of the bore 24. The rear end of the spring 27 is bent as at 28 in embracing relation about the lower portion of the trigger bar C and this portion seats in a groove 29 provided for this purpose. The tension of the coil spring 27 is such that it normally holds the trigger bar C in the position shown in Figure 5 notwithstanding the bands 50 55

when mounted on the body exert a pressure in the opposite direction.

The forward end of the barrel 10 has a segmental shaped depression or recess 29 therein which aids to retain the forward end of the bands 18, 19 in position. The opposite sides of the barrel 10 have a slight taper inwardly and forwardly from the slot C which permits the bands to be projected with reasonable accuracy.

10 The forward and rear edges indicated respectively at 30, 31 of the trigger bar C are straight.

In using the toy firearm to project rubber bands it will be understood that the length of the barrel 10 from the handle 11 should be chosen so that the resultant tension of the bands 18, 19 will not be strong enough to overcome the tension of the spring 23 because it is the purpose of this invention to have the spring normally retain the trigger bar in cocked relation.

15 20 The intermediate portion of a pair of bands, 18, 19 embrace the intermediate portion of the barrel and the ends of the bands fit over the recess 29 in the forward end of the barrel. The rear end of the bands fit in the rear edge of the trigger bar which is of compound curvature. The upper band 19 fits in the segmental notch 20, while the lower band 18 fits in the notch 21. Partial movement of the trigger will first release the upper band 19. Then further movement will 25 30 release the lower band 18. If it is the desire to release both bands 18, 19 simultaneously then the trigger bar is rocked to the forward position shown in Figure 6 in the drawings without pause. As a means to further enhance the appearance 35 to simulate a firearm I mount a trigger guard 32 in the angle between the extension 23 and the handle 11. The trigger guard 32 surrounds the projecting finger grip 16.

Having described the invention, what is 40 claimed is:

1. A toy firearm for shooting rubber bands formed of a body portion including a barrel, a handle depending from the rear end of the barrel, and a bored extension under an intermediate 45 portion of the barrel; said barrel formed with a slot registering with one end of the bore in the extension, a trigger bar pivoted to oscillate on

a fixed axis in the slot and having portions extending above and below the barrel to form respectively a projectile band gripping portion and finger gripping portion, a spring having one end fixed in the bore and connected to the trigger bar at the other end to normally retain the trigger bar under continual tension in one direction in opposition to the tension of the bands, the muzzle of the barrel being provided with a recess to hold the outer end of a rubber band embracing the sides of the barrel with the inner end of the rubber band engaged with the band gripping portion of the trigger bar, said band gripping portion being equipped with a compound curvature so as to hold a plurality of projectile bands in position to be selectively released free of the barrel at different positions of the trigger bar.

2. In a toy firearm for shooting rubber bands having a barrel simulating portion and a handle simulating portion wherein at least two rubber bands contact the muzzle of the barrel at one end and a trigger bar at the other end with intermediate portions of the band freely embracing the sides of the barrel between the trigger bar and the muzzle of the barrel; the combination with the aforesaid elements of a single elongated trigger bar mounted for limited oscillating movement on a fixed axis in the rear portion of the barrel, a portion of the trigger bar extending above and below the barrel to form respectively a band gripping portion and a trigger portion, means carried by the barrel and engaging the bar for exerting continuous tension on the bar in one direction in opposition to the tension of the bands, and the band gripping portion extending above the barrel formed with at least two band gripping notches arranged one inwardly and downwardly of the other relative to the free upper end of the bar whereby the bands may be released at different intervals during the movement of the trigger bar in the one direction against the tension of the aforesaid means.
